DRILL PIPE AND PROPELLER SHAFT

Application filed September 25, 1928. Serial No. 308,239.

This invention relates to a drill pipe and propeller shaft structure adapted for use wherein a pipe is inserted in tubing and a rotary propeller shaft disposed within the pipe string. The invention contemplates self-contained units which comprise a section of pipe and a propeller shaft, all arranged so that several units may be assembled to form a string of the length desired.

In the copending application, Ser. No. 305,190 for impact bits, filed by me Sept. 11, 1928, a bit is shown supported by a drill pipe and turnable thereby together with a rotary drive shaft for actuating mechanism to reciprocate the bit. The present invention is particularly adaptable for use with such a bit, but is not limited to such use.

The objects of this invention are first, to provide a unit comprising a section of drill pipe and a drive shaft rotatably mounted therein with ends including coupling members for adjacent units, fittings, or tools, whereby the units may be joined in assembled relation by merely connecting the pipe by screw couplings; and second, to provide such a unit with slip couplings for the shaft sections.

These objects together with other objects and corresponding accomplishments are obtained by means of the embodiment of my invention illustrated in the accompanying drawings, in which:—

Fig. 1 is an elevation partly in vertical section showing the upper end of an assemblage including a string of drill pipe comprising units, parts of the structure not pertinent to the present invention being partially shown; Fig. 2 is a vertical section through a unit joined to adjacent units which latter are shown fragmentarily; Figs. 3 and 4 are sections as seen on the lines correspondingly numbered in Fig. 2; and Fig. 5 is an enlarged fragmentary view in section showing details of the thrust bearing construction.

Referring more particularly to the drawings, 5 indicates a well hole having the usual casing 6, which in hydraulic drilling is equipped with a casing head, not shown herein. Extending into the well hole and through the casing is a drill pipe string 7 having

attached to the upper end a kelley bar 8 which is square in cross-section and slidably extends through a rotary table 9 for the purpose of rotating the drill pipe. The kelley bar and rotary table are of a well known type of construction and form no part of the present invention. The drill pipe string is swivelled to a mud chamber 10 having an inlet 11 for mud communicating with the bore of the drill pipe. Extending centrally through the drill pipe is a rotary drive shaft string 12. The upper end of the drive shaft string passes through a stuffing box 13 and is operated by an electric motor 14 mounted upon the mud chamber. Obviously, the drill pipe and the drive shaft may be rotated at different speeds.

The invention resides particularly in the units comprising the drill pipe string as best shown in Figs. 2, 3 and 4. In Fig. 2, the members of a unit are shown extending coextensive with the line marked A. A joint of pipe 15 is externally tapered at the ends as indicated by 15a and 15b. Mounted upon the end 15a is a coupling collar 16 having a box end 16a. Spanning the collar is a bearing bridge 17 suitably secured to the collar and having an opening to receive a drive shaft section 18. Secured to the lower end of the joint of pipe is a coupling collar 19 having an externally tapered and threaded pin end 19a serving for attachment to an adjoining unit having a box pin corresponding to the box end 16a. Within the coupling collar and spanning the latter is a bearing bridge 20 rotatably supporting drive shaft section 18. The drive shaft section has complementary ends serving as coupling members for slip-couplings. The upper end is shown as a box 21 having a square bore tapering downwardly. The lower end of the shaft section 18 has a square pin end 22 corresponding to the bore of the box end. The pin end is designed to be slipped within the box end of an adjoining section of drive shaft to couple them together. Secured on the drive shaft is a thrust collar 23 for engaging the bearing bridge 17 so as to support the drive section within the joint of piping.

The string of piping is set up by screwing

units to adjacent sections. The drive shaft sections will slip into coupling connections with the adjoining drive shaft sections. When the string is completed there is a continuous string of pipes having rotatably mounted within it a string of drive shaft sections all coupled together and rotatable independently in relation to the pipe. The upper end of the drive shaft extending 10 through and beyond the kelley bar is marked 12 in Fig. 1. Any suitable tool may be attached to the lower end of the drill pipe string and turned by the rotary table. The drive shaft may be independently rotated by 15 means of the motor and may be connected to such mechanism in the tool as it is desired to operate at the bottom of the pipe string.

What I claim is:

20 1. A drill pipe and drive shaft unit comprising a joint of piping with screw threaded couplings at the ends adapted for attachment to like joints, thrust bearings in said joints of piping, a drive shaft section rotatably mounted in said bearings and having 25 thrust means coacting with said bearings to maintain said drive shaft section in longitudinal placement, and slip joint coupling members at the ends of said shaft section adapted for connection to shaft sections in 30 adjoining units. 90

2. A drill pipe and drive shaft unit comprising a joint of piping with screw threaded couplings at the ends adapted for attachment to like joints, thrust bearings in said 35 joint of piping, a drive shaft section rotatably mounted in said bearings and having thrust means coacting with said bearings to maintain said drive shaft section in longitudinal placement, and complementary slip 40 joint coupling members at the ends of said shaft adapted for connection to corresponding shaft sections in adjoining joints. 100

3. A drill pipe and drive shaft unit comprising a joint of piping with screw threaded 45 couplings at the ends adapted for attachment to like joints, thrust bearings in said joint of piping, a drive shaft rotatably mounted in said bearings and having a thrust collar coacting with one of said bearings, and slip joint coupling members at the ends of 50 said shaft section adapted for connection to shaft sections in adjoining units. 115

4. A drill pipe and drive shaft unit comprising a joint of piping with screw threaded 55 couplings at the ends adapted for attachment to like joints, thrust bearings in said joint of piping, a drive shaft rotatably mounted in said bearings having a thrust collar coacting with one of said bearings and 60 complementary slip joint coupling members at the ends of said shaft section adapted for connection to corresponding shaft sections in adjoining units. 125

65 5. A drill pipe and drive shaft unit comprising a joint of pipe section threaded at its 130

ends, coupling sleeves threaded to the ends of said pipe section, one of said sleeves having a threaded pin end and the other a corresponding socket end, thrust bearings extending across said couplings, a drive shaft rotatably supported in said bearings and having thrust means coacting with one of said bearings and having complementary slip coupling members at its ends. 70

In witness that I claim the foregoing I have 75 hereunto subscribed my name this 11th day of September, 1928.
